DESIGN FOR AN ELECTRIC FAN AND HEATING DEVICE.

59,214.

Specification for Design.

Patented Oct. 4, 1921.

Application filed June 1, 1921. Serial No. 474,275. Term of patent 14 years.

To all whom it may concern:

Be it known that we, GEORGE GRAFF and WILLIAM A. KENNEDY, citizens of the United States, residing, respectively, at New York city, county of Bronx, State of New York, and Leonia, county of Bergen, and State of New Jersey, have invented a new, original, and ornamental Design for an Electric Fan and Heating Device, of which the following is a specification.

This invention relates to a new, original and ornamental design for an electric fan and heating device, and the invention consists in the peculiar shape of the same substantially as shown in the accompanying drawing forming a part of this specification, in which the figure is a perspective view of the device.

The design consists in the peculiar shape of the device with the base A, standard B, fan cover C, heat reflector surface D, and air deflector or cover E, which also may act as a container for water, the elements being used either with or without surface ornamentation.

We claim:

The ornamental design for an electric fan and heating device as shown and described.

In testimony whereof, we have hereunto set our hands.

GEORGE GRAFF.
WILLIAM A. KENNEDY.
